UNITED STATES PATENT OFFICE.

AMOS G. FITZ, OF AUBURN, MAINE, ASSIGNOR TO FITZ DOUBLE PIVOT LAST COMPANY, OF AUBURN, MAINE, A CORPORATION OF MAINE.

LAST.

933,029.

Specification of Letters Patent. Patented Aug. 31, 1909.

Application filed February 23, 1909. Serial No. 479,315.

To all whom it may concern:

Be it known that I, Amos G. Fitz, a citizen of the United States, residing at Auburn, in the county of Androscoggin and State of Maine, have invented new and useful Improvements in Lasts, of which the following is a specification.

My invention relates to improvements in lasts.

10 The main features of these improvements are shown but not claimed in my United States Patent No. 913,418, and consists in a novel construction of divided lasts wherein the last is divided transversely by lines of 15 cut which form mutually-overlapping surfaces, the parts connected by a link, the overlapping surfaces extending beyond the pivot in the fore part, and in certain details of construction hereinafter more fully set out and 20 particularly claimed.

The figure which is a vertical section shows my invention embodied in a last of the type called fillers. My invention is by no means limited to use in fillers but may be 25 used in all kinds of lasts where applicable.

Same letters of reference indicate like parts.

In said drawings A represents the toe part of the last and B the heel part and C the line 30 of division, the line of division being an irregular line extending transversely across the last. The two parts of the last are provided with vertically disposed link kerfs D and E in their respective ends and are connected by a link F mounted one end in the toe part and the other end in the heel part so 35 that the front end of the heel part can be lifted and turned upwardly and rearwardly. When the rear pivot G is higher than the 40 front pivot H the parts may be held against

accidental displacement by making the front end I of the heel part abut against the rear end J of the toe part, or the overlapping surfaces may be provided one with a projection K and the other with a depression L adapted 45 to register therewith so that any endwise pressure will tend to prevent forward movement of the heel part but will not prevent the front end thereof from being lifted upwardly and rearwardly. 50

Having thus described my invention and its use I claim:—

1. A last divided transversely by lines of cut which form overlapping surfaces, link receiving kerfs in the adjacent ends thereof, 55 a link mounted one end in the heel part and one end in the toe part, said overlapping surfaces projecting beyond the front pivot, whereby the front end of the heel part can be turned upwardly and rearwardly and means 60 for locking the two parts against accidental displacement.

2. A last divided transversely by lines of cut which form overlapping surfaces, link receiving kerfs in the adjacent ends, a link 65 mounted in said kerfs, the front end of the heel part being in locking engagement with the rear end of the toe part, said locking engagement being efficient only against longitudinal and downward pressure on the 70 front end of the heel part.

In testimony whereof, I have signed my name to this specification in presence of two subscribing witnesses this twentieth day of February, 1909.

AMOS G. FITZ.

In presence of—

JOHN A. MORRILL,
CARRIE E. WEST.
